US0D1078521S

(12) United States Design Patent (10) Patent No.: US D1,078,521 S
(45) Date of Patent:  Jun. 10, 2025

(54) WATCH DIAL

(71) Applicant: Richemont International SA,
Villars-sur-Glâne (CH)

(72) Inventors: Manfredi Calamai, Zürich (CH);
Maria Luisa Mamusa, Schaffhausen
(CH)

(73) Assignee: RICHEMONT INTERNATIONAL
SA, Villars-sur-Glâne (CH)

() Term: 15 Years

(21) Appl. No.: 29/896,145

(22) Filed: Jun. 29, 2023

Related U.S. Application Data

(62) Division of application No. 35/514,245, filed on Mar. 9, 2022 (U.S. filing date under 35 U.S.C. 384), and having an international filing date of Mar. 9, 2022, now Pat. No. Des. 997,010.
